CLAIM

The ornamental design for a display screen as shown and described.

DESCRIPTION

FIG. 1 is a front, left and top perspective view of a display screen showing my design;

FIG. 2 is a rear, right and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an exploded perspective view thereof; and,

FIG. 10 is a perspective view of another state of the display screen thereof.

The broken lines are included for the purposes of illustrating portions of the display screen that form no part of the claimed design.

1 Claim, 10 Drawing Sheets
